UNITED STATES PATENT OFFICE

172,377

SAFETY KNIFE

Cecil B. Woofter, St. Paul, Minn., assignor to
Brown & Bigelow, St. Paul, Minn.

Application October 5, 1953, Serial No. 27,070

Term of patent 14 years

(Cl. D22—3)

To all whom it may concern:

Be it known that I, Cecil B. Woofter, a citizen of the United States, residing in St. Paul, county of Ramsey, and State of Minnesota, have invented a new, original, and ornamental Design for a Safety Knife, for which the following is a specification, reference being had to the accompanying drawing, forming part thereof.

Figure 1 is a side elevational view of a safety knife, showing my new design, the side opposite presenting a similar appearance;

Figure 2 is a rear end view thereof;

Figure 3 is a top plan view;

Figure 4 is a front end view; and

Figure 5 is a side elevational view thereof as it appears in open position with the blade guard swung back onto the knife.

I claim:

The ornamental design for a safety knife, as shown and described.
